Primary Examiner — Melody N Brown**CLAIM**

The ornamental design for a vehicle rear lower bumper fascia, as shown and described.

DESCRIPTION

FIG. 1 is a front and left side perspective view of a vehicle rear lower bumper fascia showing our new design;

FIG. 2 is a left side elevation view thereof, the right side being a mirror image of the left side shown;

FIG. 3 is a front elevation view thereof; and,

FIG. 4 is a top plan view thereof.

The right end elevation view is omitted, because the right end elevation view is a mirror image to the left end elevation view.

The broken lines shown in the drawings depict portions of the vehicle rear lower bumper fascia that form no part of the claimed design.

The shade lines in the figures show contour and not surface ornamentation.
